MOTOR

John C. Curtis, Claremont, N. H., assignor to
 Sullivan Machinery Company, a corporation
 of Massachusetts

Application January 5, 1938, Serial No. 183,421

10 Claims. (Cl. 121—57)

This invention relates to motors, and more particularly, but not exclusively, to improvements in a fluid actuated motor of the rotating piston, sliding vane type.

It has heretofore been found that under certain conditions, motors of the rotating piston, sliding vane type embody advantages not present in motors of other types, especially in regard to simplicity and relatively high starting torque. It has been found, however, that in motors of this character, particularly when the piston is rotating at a relatively high speed, the vanes are thrust radially against the inner walls of the motor cylinder due to centrifugal force, and wear of the contacting surfaces of the vanes and cylinder walls due to sliding friction, and resultant leakage, power loss and noise quickly occur.

Now, according to one aspect of the present invention, the radial thrust of the vanes against the inner walls of the stationary cylinder is obviated, and the thrust of the vanes is distributed over a considerable area of the smooth inner cylindric surface of a rotating sleeve, concentric with the cylinder and carried by end plates mounted in bearings coaxial with the casing for free rotation relative to the latter. The vanes are preferably mounted on a rotating piston or rotor having its axis of rotation eccentrically disposed with respect to the axis of sleeve rotation, the vanes bearing directly against the sleeve throughout their length, and the ends of the vanes contacting with the sleeve end plates. In one embodiment, the rotating sleeve may be formed with ports for controlling the supply of motive fluid to and exhaust of fluid from the cylinder, the ports permitting the flow of fluid from the supply passage of the motor casing to the spaces between the vanes and from such spaces to the exhaust passage of the motor casing.

It is a primary object of the present invention to provide an improved rotary motor of the rotating piston, sliding vane type, wherein the disadvantages of previous motors of this type are substantially overcome. Another object is to provide an improved rotary motor of the rotary piston, sliding vane type wherein the motor cylinder is provided at least in part by a rotating sleeve mounted in the motor casing and within which the rotating motor piston is eccentrically mounted, the latter supporting the vanes which engage the inner walls of the rotating sleeve, thereby substantially eliminating wear due to sliding friction between the vanes and the motor

chamber walls. Yet another object is to provide, in a motor of the above character, an improved interlocking connection between certain of the vanes and the rotating sleeve. Other objects and advantages of the invention will, however, hereinafter more fully appear in the course of the following description, and as more particularly pointed out in the appended claims.

In the accompanying drawing there is shown, for purposes of illustration, one form which the invention may assume in practice.

In this drawing:

Fig. 1 is a view in longitudinal vertical section through the illustrative embodiment of the improved motor.

Fig. 2 is a cross-sectional view taken substantially on line 2—2 of Fig. 1.

Fig. 3 is a detail sectional view taken on line 3—3 of Fig. 1, showing the improved interlocking connection between certain of the vanes and the rotating cylinder sleeve.

In this illustrative embodiment of the invention, there is shown a stationary motor casing 1, having a suitable supporting base 2 and provided with a bore 3 closed by end closure members or casing heads 4, the latter preferably being bolted by bolts 4^a to the motor casing. Journaled concentrically within the casing bore and having its exterior periphery closely contacting the walls of the latter, is a rotating cylinder-providing sleeve 5, of cylindric form and having a bore 6. In this instance, the sleeve 5 is supported by circular end plates 7, 7 having hollow trunnions 8, projecting outwardly therefrom and journaled in bearings 9, supported within the casing heads 4. The end plates 7 have their peripheral edges arranged within counter bores 10 in the sleeve ends and are clamped to the sleeve by annular retaining nuts 11, threaded within the sleeve counter bores. Suitable gaskets may be provided between the plate edges and the bottoms of the counter bores or at other desired locations, to insure against leakage. Arranged eccentrically within the sleeve is a rotating piston rotor 12, having oppositely projecting aligned shaft portions 13, 14, extending through the hollow trunnions 8 and journaled in bearings 15 likewise supported within the casing heads 4. The axis of rotation of the rotor piston 12 is eccentrically located in parallelism with the axis of rotation of the rotating sleeve 5 so that a crescent-shaped chamber is provided between the outer periphery of the rotor and the inner walls of the sleeve. The rotor is provided with a series of equally spaced, radial slots or grooves 16, extending

throughout its length, and guided into these slots are radial vanes 17 held in their outermost extended relation by sets of oppositely acting spring-pressed plungers 18, with their outer ends 5 in engagement with the inner smooth cylindric surface of the rotating sleeve 5. The spring-pressed plungers are arranged in bores formed in the rotor, and the ends of the vanes contacting the sleeve bore are, in this instance, rounded or 10 arcuately formed at 19, to insure sealing contact of the vanes with the walls of the sleeve bore during rotation of the rotor. The crescent-shaped chamber above mentioned is divided into 15 motor-chamber spaces and each of these spaces, bounded by the inner walls of the rotating-cylinder sleeve, the outer surface of the rotor and pairs of mutually adjacent vanes, is provided with a port which acts alternatively as an inlet and an 20 exhaust port. These ports for the motor-chamber spaces are designated 20 and are formed in the rotating sleeve 5 in the manner clearly shown in Fig. 2. One of the vanes is formed with bores 21 in which are seated pins 22 having somewhat rounded-headed ends 23 engaged in recesses 24 25 formed in the sleeve 5 as shown in Figs. 1 and 3, so that the sleeve is connected to the piston rotor. As the piston rotor rotates within its bearings relative to the casing, there is a slight angular 30 rocking, substantially non-sliding movement of the vanes with respect to the sleeve, and the rounded ends of the vanes compensate for such relative angular rocking, substantially non-sliding movement, thereby insuring fluid-tight engagement between the vanes and the inner surface 35 of the sleeve, and the rounded-headed portions 23 of the connections between one of the vanes and the sleeve also permit such relative angular rocking, substantially non-sliding movement of the vanes with respect to the sleeve while 40 at all times connecting the sleeve to the rotor. As shown in Fig. 2, the stationary motor casing is provided with an inlet passage 26, connected by a pipe connection 27 to any suitable source of pressure fluid supply, and an exhaust passage 28 connected by a pipe connection 29 to a suitable point of exhaust. These supply and exhaust passages 45 26 and 28 are preferably disposed in horizontal alignment, and communicate with arcuate slots 30 and 31 respectively, formed in the walls of the bore 3 of the stationary motor casing. When the 50 direction of rotation of the motor is desired to be reversed, the discharge passage 28 may act as a supply passage and the supply passage 26 as a discharge passage.

55 The operation of the improved motor will be clearly apparent from the description given. Referring to Fig. 2, when pressure fluid is supplied through the pipe connection 27 to the supply passage 26, pressure fluid flows from the 60 groove 30 through certain of the ports 20 communicating with the groove 30 to certain of the motor chamber spaces between the inner and outer walls of the sleeve and rotor, and sets of mutually adjacent vanes; while the motor chamber spaces at the opposite side of the rotor are 65 connected, through certain of the ports 20 communicating with the groove 31, with the exhaust passage 28. The ports 20 in the rotating sleeve 5 permit pressure fluid to flow from the supply 70 passage 26 to the spaces between the vanes at one side of the motor and from such spaces at the opposite side of the motor to the exhaust passage 28, the fluid acting first at line pressure and later expansively on the effective vane surfaces, to 75 effect rotation of the piston rotor 12. The ports

20 in the sleeve 5, as they move out of communication with the arcuate grooves 30 and 31 in the casing, are closed off by the walls of the casing bore between the grooves. As the piston rotor 12 revolves within its bearings relative to the casing, the sleeve 5 rotates therewith due to the interlocking connection 23, 24 between one of the vanes and the sleeve. The spring-pressed plungers 18 hold the vanes 17 in contact with the inner surface of the sleeve to provide a tight sealing engagement between the vanes and the sleeve surface 6. 10

As a result of this invention it will be noted that an improved motor of the rotating piston, sliding vane type is provided, having improved means for eliminating, to a substantial extent, wear of the ends of the vanes contacting with the walls of the cylinder, thereby resulting in a motor which is relatively more powerful and quiet in operation. It will further be noted that 15 by the provision of the cylindric sleeve connected to one of the vanes of the rotor, the sleeve rotates with the rotor so that wear due to sliding friction between the vanes and the cylinder wall is substantially reduced. Furthermore, by forming the ports for conducting fluid to the spaces between the vanes, in the rotating sleeve, the fluid distribution means of the motor is greatly simplified. Other uses and advantages of the 20 improved motor will be clearly apparent to those 25 skilled in the art. 30

While there is in this application specifically described one form which the invention may assume in practice, it will be understood that this form of the same is shown for purposes of illustration and that the invention may be modified and embodied in various other forms without departing from its spirit or the scope of the appended claims. 35

What I claim as new, and desire to secure by 40 Letters Patent is:

1. In a motor of the character described, the combination of a stationary casing having a bore, heads closing the opposite ends of said bore, a cylindric sleeve arranged concentrically within the bore and journaled in bearings supported within the casing heads for free rotation relative to the casing, a rotor mounted eccentrically within the sleeve and journaled within the casing heads for rotation relative to the casing about an axis parallel to the axis of rotation of said sleeve, radially movable vanes guided on said rotor and arranged to bear throughout their length against the inner smooth cylindric surface of the sleeve; a connection between one of said vanes and said sleeve whereby rotation of the rotor effects rotation of the sleeve, and motive fluid supply and exhaust means for the motor including fluid supply and exhaust passages and ports in said sleeve for connecting the spaces bounded by the inner surface of the sleeve, the outer surface of the rotor and pairs of mutually adjacent vanes, with said supply and exhaust passages. 55

2. In a motor of the character described, the combination of a stationary casing having a bore, heads closing the opposite ends of said bore, a cylindric sleeve arranged concentrically within the bore and journaled in bearings supported within the casing heads for free rotation relative to the casing, a rotor mounted eccentrically within the sleeve and journaled within the casing heads for rotation relative to the casing about an axis parallel to the axis of rotation of said sleeve, radially movable vanes guided on said rotor and arranged to bear throughout their length against the inner 60 65 70 75 80 85 90 95 98

- smooth cylindric surface of the sleeve, a connection between one of said vanes and said sleeve whereby rotation of the rotor effects rotation of the sleeve, said vanes assuming different angular positions with respect to the sleeve as said rotor rotates within its bearings relative to the casing, and said inter-connection being formed to permit such relative angular movement, and motive fluid supply and exhaust means for the motor including fluid supply and exhaust passages and ports in said sleeve for connecting the spaces bounded by the inner surface of the sleeve, the outer surface of the rotor and pairs of mutually adjacent vanes, with said supply and exhaust passages.
3. In a motor of the character described, the combination of a stationary casing having a bore, heads closing the opposite ends of said bore, a cylindric sleeve arranged concentrically within the casing bore and journaled in bearings supported in said casing heads for free rotation relative to the casing, a rotor mounted eccentrically within the sleeve and journaled within the casing heads for rotation relative to the casing about an axis parallel to the axis of rotation of said sleeve, radially movable vanes guided on said rotor and arranged to bear in rocking, substantially non-sliding contact throughout their length against the inner smooth cylindric surface of said sleeve, the vanes assuming different angular relation with respect to said sleeve as said rotor rotates in its bearings relative to the casing, the ends of said vanes which bear against the inner surface of said sleeve being arcuately formed to permit such relative angular rocking movement of the vanes while maintaining a sealing engagement of the latter with the inner surface of said sleeve, means acting on said vanes for yieldingly urging the ends of said vanes into contact with the inner smooth cylindric surface of said sleeve, and motive fluid supply and exhaust means for the motor including fluid supply and exhaust passages and ports in said sleeve for connecting the spaces bounded by the inner surface of the sleeve, the outer surface of the rotor and pairs of mutually adjacent vanes, with said supply and exhaust passages.
4. In a motor of the character described, the combination of a stationary casing having a bore, heads closing the opposite ends of said bore, a cylindric sleeve arranged concentrically within the casing bore and journaled in bearings supported within the casing heads for free rotation relative to the casing, a rotor mounted eccentrically within the sleeve and journaled within the casing heads for rotation relative to the casing about an axis parallel to the axis of rotation of said sleeve, radially movable vanes guided on said rotor and arranged to bear in rocking, substantially non-sliding contact throughout their length against the inner smooth cylindric surface of said sleeve, means for connecting said sleeve to said rotor whereby rotation of said rotor about its axis causes rotation of said sleeve, and motive fluid supply and exhaust means for the motor including fluid supply and exhaust passages and ports in said sleeve for connecting the spaces bounded by the inner surface of the sleeve, the outer surface of the rotor and pairs of mutually adjacent vanes, with said supply and exhaust passages.
5. In a motor of the character described, the combination of a stationary casing having a bore, heads closing the opposite ends of said bore, a cylindric sleeve arranged concentrically within the casing and at its exterior periphery having a close running fit with the walls of the casing bore, said sleeve journaled in bearings supported within the casing heads for free rotation relative to the casing, a rotor mounted eccentrically within the sleeve and journaled within the casing heads for rotation relative to the casing about an axis parallel to the axis of rotation of said sleeve, radially movable vanes guided on said rotor and arranged to bear throughout their length against the inner smooth cylindric surface of said sleeve, an interconnection between one of said vanes and said sleeve whereby rotation of said rotor effects rotation of the sleeve, supply and exhaust passages in the motor casing, and ports in said sleeve for connecting the spaces bounded by the inner surface of said sleeve, the outer surface of the rotor and pairs of mutually adjacent vanes, with said supply and exhaust passages.
6. In a motor of the character described, the combination of a stationary casing having a bore, casing heads closing the opposite ends of said bore, a cylindric sleeve arranged concentrically within the casing bore with its outer peripheral surface having a tight running fit with the walls of the casing bore, circular end plates supporting said sleeve and having hollow trunnions journaled in bearings supported by said casing heads for mounting said sleeve for free rotation relative to said casing, a rotor mounted eccentrically within said sleeve and having oppositely extending shaft portions journaled in bearings supported by said casing heads, said shaft portions extending through said hollow trunnions and arranged with their axes in parallelism with the axis of rotation of said sleeve, radially located vanes guided on said rotor and having their outer ends bearing in rocking, substantially non-sliding contact against the inner smooth cylindric surface of said sleeve, means for constantly yieldingly urging said vanes to bear against the inner cylindric surface of said sleeve, means for connecting said sleeve to said rotor so that when the rotor revolves the sleeve is rotated thereby, and means for supplying fluid to and exhausting fluid from the spaces bounded by the inner surface of the sleeve, the outer surface of the rotor and mutually adjacent pairs of vanes including ports formed in said sleeve and supply and exhaust passages in the motor casing and with which said ports are communicable.
7. In a motor of the character described, the combination of a stationary casing having a bore, casing heads closing the opposite ends of said bore, a cylindric sleeve arranged concentrically within the casing bore with its outer peripheral surface having a tight running fit with the walls of the casing bore, circular end plates supporting said sleeve and having hollow trunnions journaled in bearings supported by said casing heads for mounting said sleeve for free rotation relative to said casing, a rotor mounted eccentrically within said sleeve and having oppositely extending shaft portions journaled in bearings supported by said casing heads, said shaft portions extending through said hollow trunnions and arranged with their axes in parallelism with the axis of rotation of said sleeve, radially located vanes guided on said rotor and having their outer ends bearing in rocking, substantially non-sliding contact against the inner smooth cylindric surface of said sleeve, means for constantly yieldingly urging said vanes to bear against the inner cylindric surface of said sleeve, an interlocking connection between one of said vanes and said sleeve so that when the rotor revolves the sleeve is rotated thereby, and means for supplying fluid to and exhausting fluid from the spaces bounded by the inner surface of the sleeve, the outer surface of the rotor and mutually adjacent pairs of vanes including ports formed in said sleeve and supply and exhaust passages in the motor casing and with which said ports are communicable.

- adjacent pairs of vanes including ports formed in said sleeve and supply and exhaust passages in the motor casing and with which said ports are communicable.
5. 8. In a motor of the character described, the combination of a stationary casing having a chamber provided with end walls, a cylindric sleeve journaled in said chamber for free rotation relative to said casing, a rotor mounted eccentrically within said sleeve and journaled within said casing on an axis parallel to the axis of sleeve rotation, vanes guided for radial movement on said rotor and arranged to bear against the smooth inner cylindric surface of said sleeve, an 10 interlocking connection between one of said vanes and said sleeve whereby rotation of said rotor effects rotation of the sleeve, and motive fluid supply and exhaust means for the motor for supplying fluid thereto and exhausting fluid therefrom including fluid supply and exhaust 15 ports in said rotatable sleeve.
15. 9. In a motor of the character described, the combination of a stationary casing having a chamber provided with end walls, a cylindric sleeve journaled in said chamber for free rotation relative to said casing, a rotor mounted eccentrically within said sleeve and journaled within said casing on an axis parallel to the axis of sleeve 20 rotation, vanes guided for radial movement on said rotor and arranged to bear in rocking, substantially non-sliding contact with the smooth inner periphery of said sleeve, means for connecting said sleeve to said rotor whereby rotation of said rotor effects rotation of said sleeve, and motive fluid supply and exhaust means for the motor for supplying fluid thereto and exhausting fluid therefrom including fluid supply and exhaust 25 ports in said rotatable sleeve.
20. 10. In a motor of the character described, the combination of a stationary casing having a chamber provided with end walls, a cylindric sleeve journaled in said chamber for free rotation relative to said casing, a rotor mounted eccentrically within said sleeve and journaled within said casing on an axis parallel to the axis of sleeve rotation, vanes guided for radial movement on said rotor and arranged to bear in rocking, substantially non-sliding contact with the smooth inner periphery of said sleeve, an interlocking connection between one of said vanes and said sleeve whereby rotation of said rotor effects rotation of said sleeve, and motive fluid supply and exhaust means for the motor for supplying fluid to and exhausting fluid therefrom including fluid supply and exhaust ports in said rotatable sleeve.
